Patented Aug. 18, 1914

UNITED STATES PATENT OFFICE.

HORATIO G. GILLMOR, OF BATH, MAINE.

RAIL-JOINT.

1,107,419.

Specification of Letters Patent. Patented Aug. 18, 1914.

Application filed August 21, 1906. Serial No. 331,527.

To all whom it may concern:

Be it known that I, HORATIO G. GILLMOR, a citizen of the United States, residing at Bath, in the county of Sagadahoc, State of Maine, have invented certain new and useful Improvements in Rail-Joints, of which the following is a specification, accompanied by drawings.

This invention relates to rail joints; and one of its objects is to so form such joints as to overcome the tendency to vertical movement of one rail end relative to the other as the wheels pass from one rail end to another.

Another object is to provide cheap and simple means for strengthening rail joints, which have been or are in use, by adding to parts already in use one or more parts which may be produced by rolling.

Another object is to increase the area of contact of the parts of the joint with the rails and to secure pressure of the parts of the joint upon the upper and lower surfaces of the base flanges of the rails.

Another object is to provide for securely locking the nuts upon the bolts securing the fish bars in position.

Further objects of the invention will hereinafter appear; and to these ends the invention consists of a rail joint for carrying out the above objects embodying the features of construction, combination of elements and arrangement of parts having the general mode of operation as hereinafter described and claimed in this specification and shown in the accompanying drawings, in which—

Figures 1 and 2 are, respectively, a transverse sectional view at the line X X and a side elevation, partly in section, of a joint embodying the invention. Figs. 3 and 4 are, respectively, a transverse section at the line Y Y and a plan view of a joint using a modified form of the clamp bars.

Referring to the drawings: A represents the meeting ends of the rails.

B represents fish bars of the usual type, held in position by bolts C fitted with nuts D.

E is a base plate overlapping the rail ends, upon which the rails rest. This base plate has upwardly projecting lugs F which interlock with corresponding notches in the fish bars.

G represents clamp bars or clamps having a longitudinal stiffening flange H.

One of the features of this invention resides in the fact that pressure is exerted by the parts of the joint upon the upper and lower surfaces of the base flanges of the rails in addition to the usual pressure of the fish bars upward under the heads of the rails and downward upon the upper surfaces of the base flanges. These ends are obtained by employing the clamps G. After the fish bars have been applied in the usual manner and the nuts well set up on their bolts to draw the fish bars into position; the bars G are applied with the arms I, which are at an angle to the body of G, engaging with the flange of the fish bars while the body of G engages with the bottom of the base plate. The bars G are then driven into position by lateral blows with suitable hammers or mauls and when so driven effectually clamp the base flanges of the meeting rail ends between the base plate and the fish bar flanges. To retain the bars G in position, their stiffening flanges H are pierced with suitable holes and bolts K are inserted and nuts set up on them. By setting up the nuts L simultaneously with driving the bars into position, the operation of driving these latter into place is facilitated. The flanges I possess some elasticity so that the nuts may be finally set up sufficiently to spring these flanges. The effect of this is to lock the nuts L against slackening and to prevent slackening of the clamps even though the nuts L should move somewhat on their bolts. The arms I of the clamps are so constructed that, when the clamps are in place, one or both of the arms I will come below and in such proximity to a part or all of the nuts D, by which the fish bars B are secured in position, as to prevent these from turning upon their bolts more than a very small amount without coming into contact with I, and so being locked against further slackening.

The bolts traversing the rails and the fish bars secure the rails against all but small movements relative to the fish bars. The lugs F on the base plate engaging with notches in the flanges of the fish bars, lock the fish bars and the base plate. The base plate is also notched to receive the clamp bars G. The portions of the base plate

coming upon the sleepers have suitable spiking apertures and spikes M, a part or all of which engage also with notches in the fish bar flanges registering with the apertures in the base plate, are driven into the sleepers through the apertures in the base plate. In this way the parts are effectually secured to the ties and the tendency to bodily movement of the rails resisted by the ballasting material in which the ties are set.

The modified form of the joint illustrated in Figs. 3 and 4 differs from that just described in that the stiffening flanges I project upward instead of downward and are provided with holes to receive the projecting ends of the bolts C used in securing the fish bars in position. The nuts L applied to these bolts retain the clamp bars G in position, the flange I of the clamp bars G springing as previously described to exert a locking action upon these nuts. The base plate is omitted in this modified form of the joint and the clamps made longer and provided with horizontally extending flanges N which have spiking apertures through which the spikes M are driven to secure the parts to the ties.

While bolts have been shown for securing the clamp bars G in position, other means, such for example as split pins, etc., might be employed for the purpose.

Obviously some features of this invention may be used without others, and the invention may be embodied in widely varying forms.

Therefore, without limiting the invention to the constructions shown and described nor enumerating equivalents, I claim and desire to secure by Letters Patent the following:

1. A rail joint, including, in combination with the rails and fish bars, a base plate and a clamp bar constructed with a base engaging with the base plate, an arm integral with said base at an angle thereto engaging with surfaces of a fish bar above the bases of the rails and a longitudinal stiffening web integral with and projecting from the base of said clamp bar, substantially as described.

2. A rail joint, including, in combination with the rails, a fish bar, a base plate, and a clamp, constructed with a longitudinal stiffening flange and two jaws to bear upon the base plate beneath and the fish bar above the bases of the rails, substantially as described.

3. A rail joint, comprising the rails, fish bars, a clamp constructed with a longitudinal stiffening web and two jaws to bear upon the base plate underneath and a fish bar above the bases of the rails, substantially as described.

4. A rail joint, including, in combination with the rails and fish bars, a base plate, a

clamp constructed with a longitudinal stiffening flange and two jaws constructed to bear upon the base plate underneath and a fish bar above the bases of the rails and means for securing said clamp in position.

70

5. A rail joint comprising the rails, fish bars, a base plate, clamps, at opposite sides of the rails, constructed with longitudinal stiffening webs or flanges and two jaws adapted to bear upon the base plate underneath and a fish bar above the bases of the rails, and means for securing said clamps in position, for substantially the purposes set forth.

75

6. A rail joint comprising the rails, fish bars having flanges, a base plate, having upwardly extending lugs, interlocking with the flanges of the fish bars, and suitable spiking apertures, a clamp, constructed to engage with the parts of the joint, produce a downward pressure upon the upper and an upward pressure upon the lower surfaces of the bases of the rails, and interlock with the base plate, means for securing the said clamp in position, and spikes traversing the spiking apertures of the base plate, for substantially the purposes set forth.

80

7. A rail joint, comprising the rails, fish bars, having flanges, a base plate, having upwardly extending lugs, interlocking with 90

the flanges of the fish bar, and suitable spiking apertures, a clamp, of substantially uniform section, constructed to engage with the parts of the joint, produce a downward pressure upon the upper and an upward pressure 100 upon the lower surfaces of the bases of the rails, and interlock with the base plate, means for securing the said clamp in position, spikes traversing the spiking apertures of the base plate, for substantially the purposes set forth.

105

8. A rail joint, comprising the rails, fish bars, having flanges, a base plate, having upwardly extending lugs, interlocking with 110

the flanges of the fish bars, and suitable spiking apertures, clamps, constructed to engage with parts of the joint, produce a downward pressure upon the upper and an upward pressure upon the lower surfaces of the bases of the rails, and interlock with 115

the base plate, means for securing the said clamps in position, and spikes, traversing the spiking apertures in the base plate, for substantially the purposes set forth.

120

9. A rail joint, comprising the rails, fish bars having flanges, a base plate, having upwardly extending lugs, interlocking with 125

the flanges of the fish bars, and suitable spiking apertures, clamps, of substantially uniform section, constructed to engage with the parts of the joint, produce a downward pressure upon the upper and an upward pressure upon the lower surfaces of the bases of the rails, and interlock with the base plate, means for securing said clamps 130

in position, and spikes traversing the co-operating apertures in the base plate, for substantially the purposes set forth.

10. A rail joint, comprising the rails, fish bars having flanges, a base plate having upwardly extending lugs, interlocking with the flanges of the fish bars, and suitable spiking apertures, two clamps, constructed to engage with parts of the joint at opposite sides of the rails, produce a downward pressure upon the upper and an upward pressure upon the lower surfaces of the bases of the rails, and interlock with the base plate, means for securing said clamps in position, 15 and spikes, traversing the spiking apertures in the base plate, for substantially the purposes set forth.

11. A rail joint, comprising the rails, fish bars having flanges, a base plate, having up-

wardly extending lugs, interlocking with the flanges of the fish bars, and suitable spiking apertures, two, substantially like, clamps, of substantially uniform section, constructed to engage with parts of the joint at opposite sides of the rails and produce a downward pressure upon the upper and an upward pressure upon the lower surfaces of the bases of the rails, means for securing said clamps in position; and means for securing said joint to the sleepers. 20 25 30

In testimony whereof, I have signed my name to this specification in the presence of two subscribing witnesses.
